Primary Examiner — George D Kirschbaum*Assistant Examiner* — Natasha Vujcic(74) *Attorney, Agent, or Firm* — Lathrop & Gage LLP(57) **CLAIM**

The ornamental design for an enlarged portion of a tire tread, as shown and described.

DESCRIPTION

FIG. 1 is a front elevation of an enlarged portion of a tire tread showing the new design on the front of a tire; and, FIG. 2 is a perspective view thereof.

The broken lines in the drawings depict environmental subject matter only and form no part of the claimed design.
